UNITED STATES PATENT OFFICE.

OTTO PEARSON, OF MOUNT JEWETT, PENNSYLVANIA.

SLED.

1,244,075.

Specification of Letters Patent. Patented Oct. 23, 1917.

Application filed February 26, 1917. Serial No. 151,049.

To all whom it may concern:

Be it known that I, OTTO PEARSON, a citizen of the United States, residing at Mount Jewett, in the county of McKean and State 5 of Pennsylvania, have invented certain new and useful Improvements in Sleds; and I do declare the following to be a full, clear, and exact description of the invention, such as will enable others skilled in the art to 10 which it appertains to make and use the same.

My invention has for its object to improve upon the construction shown in my U. S. Patent No. 1,183,228, issued May 16th, 15 1916, the improvement residing in the provision of means for preventing each front leg of the front bench or knee from shifting rearwardly in respect to the runners in case it strikes any object.

With the foregoing object in view, the invention resides in certain novel features of construction and unique combinations of parts to be hereinafter fully described and claimed, the descriptive matter being supplemented by the accompanying drawing 20 which constitutes a part of this application and in which:—

Figure 1 is a side elevation of a portion of the sled with part of the front bench leg 30 broken away to disclose one form of the means employed for preventing rearward movement of the fastener by which said leg is secured to the runner;

Fig. 2 is an enlarged perspective view of 35 a portion of the runner shown in Fig. 1;

Fig. 3 is a view similar to Fig. 2 showing the application of a different form of stop means;

Fig. 4 is a horizontal section of Fig. 3; 40 and

Figs. 5 and 6 are perspective views showing other forms of the stop devices.

In the drawing above briefly described, the numeral 1 has reference to the body of 45 a sled of the type in which the runners 2 are flexed by operation of a steering bar 3 to guide the sled, the usual front bench or knee 4 being provided for supporting the body 1 from the runners 2. The rear legs 5 50 of the bench 4 are secured to the vertical webs of the runners 2 in any suitable manner as by rivets 6 passing through circular openings in these parts. The rivets 7 by which the front legs 8 are secured to said 55 runners, however, pass through longitudinal

slots 9 in said webs, said slots being provided for the purposes set forth at length in the patent above referred to. As before suggested, the present invention aims to prevent rearward shifting of the fastener 7 in 60 the slot 9 without destroying the function of said slot. To this end, any of the structures now to be described or analogous forms may be provided.

In Figs. 1 and 2, a stop 10 extends between the fastener 7 and the rear end of the slot 9, said stop being formed by part of the vertical web of the runner as shown.

In Figs. 3 and 4 the stop 10^a is in the form of a flat plate stamped from a single piece 70 of metal for contact with one side of the runner, said plate having at one end an opening 11 through which the fastener 7 is adapted to extend, while its other end is formed with an integral tongue 12 bent laterally and then continued in a plane parallel with that of the plate, said tongue being adapted to extend through the rear end of the slot 9 and to abut said end as shown clearly in the drawing. 80

In Fig. 5, the stop 10^b is identical with that illustrated in Figs. 3 and 4 with the exception that it is provided with a pair of tongues 12^a on its opposite ends and shaped in the same manner as the tongue 12, this 85 form of the device having an opening 11^a to receive the bolt or rivet 7.

Fig. 6 depicts yet another type of the stop. In this view the plate 10^c is provided at its rear end with a tongue 12^b to pass 90 through the slot 9, while its front end is formed with a notch 11^b through which the fastener 7 is designed to extend.

Regardless of the type of stop employed, rearward movement of the front legs 8 of 95 the bench 4 will be prevented in case said legs strike objects while the sled is in use and thus bending and distorting of said legs is reduced to a minimum.

In the foregoing I have described the preferred forms of the stop and in the drawing such forms have been illustrated, but it is to be understood that within the scope of the invention as claimed, numerous changes may be made without sacrificing the principal 100 objects.

I claim:—

1. The combination with a sled having laterally flexible runners formed with longitudinal slots at substantially their bend- 110

ing points, and fasteners passing through one end of said slots for securing said runners to the body of the sled; of means for preventing movement of said fasteners in 5 said slots.

2. The combination with a sled having laterally flexible runners formed with longitudinal slots at substantially their bending points, and fasteners passing through one 10 end of said slots for securing said runners to the body of the sled; of means interposed between said fasteners and the other end of said slots for preventing movement of said fasteners in said slots.

15 3. A stop device of the class described comprising a metal plate having an opening

therethrough to receive a fastener and having on one end a tongue extending laterally.

4. A stop device of the class described comprising a flat metal plate having an 20 opening therethrough to receive a fastener and having a tongue on one of its ends bent laterally and then bent into a plane substantially parallel with that of said plate.

In testimony whereof I have hereunto set 25 my hand in the presence of two subscribing witnesses.

OTTO PEARSON.
